(57) **CLAIM**

The ornamental design for a cassette clamp for electrophoresis gel casting, as shown and described.

DESCRIPTION

This application is related to U.S. Design patent application Ser. No. 29/545,637, filed Nov. 13, 2015, entitled "Rig for Electrophoresis Gel Casting," the entire contents of each of which are incorporated by reference herein.

FIG. 1 is a front perspective view of a cassette clamp for electrophoresis gel casting showing our new design.

FIG. 2 is a back perspective view thereof.

FIG. 3 is a front view thereof.

FIG. 4 is a back view thereof.

FIG. 5 is a right side view thereof.

FIG. 6 is a left side view thereof.

FIG. 7 is a top view thereof; and,

FIG. 8 is a bottom view thereof.

The broken lines in the drawings depict portions of the cassette clamp for electrophoresis gel casting that form no part of the claimed design.
